UNITED STATES PATENT OFFICE.

WILLIAM WERNER, OF MEXIA, TEXAS.

FOUNDATION FOR STANDARD DRILLING AND PUMPING RIGS.

Application filed February 27, 1925. Serial No. 12,142.

My invention relates to an improved structure in the foundation of the so-called standard rig employed principally in cable tool drilling and also for pumping apparatuses.

The present type of foundation upon which the standard rig is mounted is customarily made of wood. This material for a foundation in oil field work is objectionable in that it is subject to decay quickly in swampy neighborhoods, and is also subject to distortion under strain in use.

It is an object of my invention to provide a concrete base, and the invention lies partly in the construction of the base itself, and partly in the manner of anchoring the rig to the base. In the construction of the base it is an object to provide for the contraction and expansion of the same, due to weather conditions. It is also an object to provide an anchoring means for the various portions of the rig, and it is desired to form a mounting for the posts of the band wheel whereby it may be adjusted to allow for the tensioning of the belt by which it is driven. These and other objects and advantages will be set forth with more particularity in the specification which follows.

Referring to the drawing herewith, Fig. 1 is a side elevation of the band wheel and adjacent parts, the base being partly in section for purposes of clearness. Fig. 2 is a top plan view of the concrete base with the rig mounted thereon. Fig. 3 is a front elevation of the band wheel and its base illustrating in section the method of anchoring the band wheel support to the concrete foundation. Like numerals of reference are employed to designate like parts in all the views.

In the construction of the concrete base for the rig, it is understood of course that the base must form a foundation for the rig itself, and also furnish a support for the derrick platform upon which the drilling operations are carried on, and in the plan view as shown in Fig. 2, the plan outline of the foundation is shown. There are preferably two longitudinal members 1 and 2, which extend from the band wheel through to the derrick platform.

Midway of the longitudinal members 1 and 2 is a transverse member 3, this portion being somewhat heavier and made stronger

than the remainder of the rig to support the band wheel thereon. At the forward end of the longitudinal members is a second transverse member 4 connecting the ends of the longitudinal members and furnishing a base for the Sampson post upon which the walking beam is mounted. On the rearward side of the base, the longitudinal members are somewhat narrower and extend through to connect with the engine base, not shown. Laterally extending supporting members 5 on the side toward the Sampson post are provided to furnish a support for the platform upon which the operators may stand.

In constructing the base it is contemplated that the expansion and contraction of the same under changes of temperature will be provided for by the inclusion in the base of vertical plates 6 set transversely of the longitudinal members and similar plates 7 set parallel with the longitudinal members and transversely of the members 3 and 4. These plates extend from the surface of the foundation through to the bottom and are preferably made of metal. Said plates are formed with transverse openings therein to receive reinforcing rods 8 set in the base in the usual manner. These rods are of sufficient length to extend from one of the plates 6 or 7 to the adjacent plate and are connected through the openings in said plates and in position therein by being turned back against the plate, as illustrated at 9 in Fig. 1. This provision allows for the expansion or contraction of the base without materially affecting its strength.

The various parts of the rig structure are anchored to the base in such manner as to allow their detachment therefrom, when desired.

In forming a seat for a post such as the Sampson post 18, a seat may be formed in the cement structure of the base, such as disclosed in Fig. 1.

Said post 18 is held downwardly within its socket, thus provided, by means of bracing rods 25 on each side thereof. As shown in Fig. 1, these rods may have a turn buckle 26 therein to adjust the tension of the same, and the upper end is formed into a hook 27 secured about a pin or bolt 28 fixed within the body of the post. The lower end of the brace rod is secured to the upper end of the anchor rod 17 secured within the base.

somewhat as shown in Fig. 3. Further brace rods 29 may be formed toward the upper end of the Sampson post and extended laterally for attachment to anchoring rods 17 at desired points.

The jack posts 30 which support the band wheel 31 are preferably made of pipe sections, the lower ends of which are screwed within T-shaped couplings 32. The said T's 10 are connected at each lateral end to sections of pipe 33 forming the base thereof. The base 33 is set within a longitudinal trough or recess 34 formed transversely of the concrete base. This recess or trough flares outwardly toward the upper end so as to allow lateral movement of the upper ends of the jack posts. The said base 33 is secured against removal within the foundation by means of U-shaped anchor rods 35. A plurality of these are provided, it being understood that as many will be employed as are necessary to fix the base firmly to the foundation. The upper end of these rods are looped over the base 33 and the lower ends 25 are extended laterally at 36 and are understood as being fixed in position during the construction of the foundation.

The upper ends of the jack post are provided with bearings for the shaft 37 of the 30 band wheel. These bearings comprise upper plates 38, and lower plates 39, said plates being held in position on the post and held in locking position upon the shaft 37 by means of rods 40. Said rods are U-shaped, 35 being held in position at their upper ends by nuts 41, the lower loop of the U-shaped rod engaging below the coupling T's 32 previously described.

The said rods 40 also furnish attachment 40 for the upper ends of brace rods 42 and 43 at opposite sides of the said posts. The rod 42 is extended forwardly and anchored at its lower end to an anchor rod 17 secured detachably within the base after the manner 45 of the showing in Fig. 1. Locking pins 13 for the post in which the rod 17 is secured, are in this particular construction extended downwardly at an angle, as illustrated in the drawing.

50 A turn buckle is provided within the two opposite rods 42, as shown best in Fig. 2. This turn buckle is made up of a centrally threaded rod 44. This rod is engaged at each end within threaded collars 45 at the ends of 55 the adjacent sections. Said rod 44 is threaded so that when rotated it will be screwed inwardly or outwardly relative to said collars at both ends simultaneously. The rod is adapted to be rotated by a sprocket chain 47 connected to sprocket wheels 48 formed upon the said rods 44. This provides for the simultaneous operation of both turn buckles so that the adjustment in lengths of the said rods will be uniform at both ends of the 60 shaft 37.

The stay bolt 43 is anchored in the base in approximately the same manner as is the rod 42. It has a common type of turn buckle 49 thereon and also may be lengthened or shortened by an adjustable connection at 70 50 between the upper end 48 of the rod and side plates 51 connecting the same with the end of the turn buckle.

The band wheel 31 is of ordinary construction, and is intended to receive a belt extending from the engine to said wheel, thus providing a means of rotating the shaft 37 upon which the crank arm is formed in the usual manner. A grooved plate 52 at one side of the band wheel allows the connection of the 80 band wheel with adjacent operative members through a cable connection, as is usual on this type of construction.

While the particular construction of the ordinary parts of the standard rig are not 85 a part of my invention, it is noted that bearing plates 54, 54' are provided in connection with the base to receive the sand reel shaft 55 shown in Fig. 1, and it is understood that said plates are mounted on blocks anchored 90 detachably to the base, as already described, so that the block 54' may be adjusted as to position when desired.

In operating the band wheel it is very frequently the case that the drive belt between 95 the engine and the wheel becomes loosened through wear and strain. The belt must be kept taut at all times and under some strain so that no slipping of the belt may occur. When the belt becomes loosened the matter 100 of tightening it becomes a more or less serious proposition in that it involves very careful adjustment and the placing it in position after it has been shortened is exceedingly difficult.

105 The provision for anchoring the jack post 30 shown and described, allows the band wheel to be tightened or loosened without difficulty, it being only necessary to adjust the turn buckles within the brace rods 42 and 43. It is apparent that these may be very readily operated, and the post 30 may assume a position slightly to one side of the vertical without interfering with the firm support for the wheel. This means of adjustment is an important improvement in the art, and is considered a point of novelty 110 in my invention.

115 Further objects and advantages will be apparent to those skilled in the art. What I claim as new, and desire to protect by Letters Patent is:

1. In a device of the character described, a concrete foundation, a plurality of jack posts secured at their lower ends to a cylindrical base, said base being seated in a trough in said foundation, means to secure said base rotatably to said foundation, and means to adjust the position of the upper end of said posts.

2. In a device of the character described, a concrete foundation having a downwardly tapered trough therein, an approximately cylindrical base member therein, upright posts on said base member, rods anchored in said base securing said base member rotatably in position in said trough, brace rods secured to the upper end of said posts and means to adjust the length of said brace

25 posts and turn buckles in said braces to adjust the positions of the upper ends of said posts.

5 5. In a device of the character described, a concrete foundation, a base member, means to secure said member adjustably to said foundation, a pair of jack posts secured to said base, bearing caps thereon, rods anchored about said base member to retain said caps in position, and longitudinally adjustable brace rods connected with said caps 30 and said foundation.

10 15. 6. In a device of the character described, a concrete foundation, a trough therein, a tubular base member in said trough, anchoring staples securing said base member adjustably in said trough, posts on said base member, caps on said posts, means connecting said caps and said base member, and inclined longitudinally adjustable rods connecting said caps with said foundation.

15 20. 4. In a device of the character described a foundation having an upwardly diverging trough therein, a cylindrical base member in said trough, means to retain said member rotatably in said trough, shaft supporting posts fixed to said base, oppositely extending brace rods at the upper ends of said

35 40 45 In testimony whereof I hereunto affix my signature this February, A. D. 1925.

WILLIAM WERNER.
